CHARLES L. PEIRCE, JR., OF PITTSBURGH, PENNSYLVANIA, ASSIGNOR OF ONE-HALF TO HUBBARD & CO., OF PITTSBURGH, PENNSYLVANIA, A CORPORATION OF PENNSYLVANIA.

INSULATOR-SUPPORT.

1,195,263.

Specification of Letters Patent.

Patented Aug. 22, 1916.

Application filed February 5, 1916. Serial No. 76,304.

To all whom it may concern:

Be it known that I, CHARLES L. PEIRCE, Jr., a citizen of the United States, and a resident of Pittsburgh, in the county of 5 Allegheny and State of Pennsylvania, have invented certain new and useful Improvements in Insulator-Supports, of which the following is a specification.

My invention relates to insulator supports 10 and contemplates improved construction which will make such supports more practical and more efficient.

The prior art discloses insulator supports in which thimble structures of thin sheet 15 metal are secured to bracket members of heavier metal, the purpose of the thin sheet metal thimble structures being to give a resilient seat to insulators. In other structures the bracket members are of heavy 20 metal and the thimble structure is integral therewith. The supports having the thin sheet metal thimble structures secured thereto are adapted only for comparatively light 25 service, and the supports in which the thimble structures are integral with the bracket part are particularly adapted for heavy service and considerable yield and elasticity of the thimble structure is sacrificed in behalf of strength.

One of the important objects of my invention is to produce a support which possesses great strength yet which is yielding at the thimble structure and which is particularly adapted for intermediate service, 35 that is, service where a thin sheet metal structure would be too weak and where the integral thimble construction would be too unyielding.

In some of the prior supports in which 40 an all sheet metal thimble structure is applied to a bracket member, the bracket member is bent up from stock material, such as channel bar. However, with such construction it is necessary to flatten and bend the 45 thimble structure in order that it may be secured to the bracket member and such bending of course destroys the circular cross-section at the lower end of the thimble structure and correspondingly reduces 50 the strength.

Another object of my invention is therefore to produce an insulator support which

will provide a seat of circular cross-section for the insulator structure so that circular cross-section throughout the insulator receiving end of the support may be retained.

I obtain the above desirable features by bending up a properly dimensioned flat piece of sheet metal to form to get the necessary strength at the various sections and 55 by having one end of the bracket member formed and threaded to form part of a thimble structure, the remaining part of the thimble structure being formed up from thinner sheet metal and secured to the 60 bracket member in such manner that the insulator receiving end of the support is of circular cross-section throughout and yielding.

My improved construction is embodied in 70 the structures shown on the accompanying drawing in which—

Figure 1 is a side elevational view, Fig. 2 is a front elevational view, Fig. 3 is a sectional view on plane 3—3, Fig. 2, Fig. 4 is 75 a sectional view on plane 4—4, Fig. 1, and Fig. 5 is a front elevational view of the thimble end of the support showing a modified arrangement.

The bracket member B shown is bent up 80 from a single piece of sheet metal to be of arched or U-shaped cross-section, the bracket member being open outwardly, that is, the limbs 10 and 11 extending outwardly and being separated to be parallel with each 85 other or at an angle. Near the outer end of the bracket member the limbs 10 and 11 are brought together to form the base part e of circular cross-section. Part of the bracket end is continued beyond this base 90 section to form the part 12 of the thimble structure. In Figs. 1 to 4, this part is semi-cylindrical and has the threads 13 thereon for insulators. The end 12 thus forms one half of the thimble structure, and the other 95 half 14 of the thimble structure is formed entire from a piece of sheet metal which is of smaller gage than the metal of the bracket B. This part 14 is semi-cylindrical and intimately engages at its lower end 100 with the cylindrical base section e and is secured thereto as by a rivet 15 extending through the base section. The upper portion of the thimble part 14 has threads 16

which register with the threads 12 to form the threaded seat for insulators. In order to make the thimble structure yielding the edges of the parts 12 and 14 are separated 5 by a gap 17, this permitting radial yield of the parts, particularly the thinner part 14, when an insulator is applied, and after application of an insulator the outward springing tendency of the parts will lock 10 the insulator to the support. The thimble receiving end of the described support is of circular cross-section throughout and maximum strength is obtained where it is mostly needed.

15 In Figs. 1 to 4, the thimble structure comprises two parts separated by gaps 17. If greater resiliency or yield is desired either one or both of these parts could be subdivided.

20 In Fig. 5 I have shown an arrangement in which the integral part of the thimble structure is sub-divided by a gap 18 into two sections *a* and *b*, and the attached thimble structure which is sub-divided by gap 25 19 into the sections *c* and *d*. The subdivision could be carried further if desired.

In the drawing I have shown the integral part 12 of the thimble structure on the inside of the bracket end, and the attachable thimble part 14 at the outside. This is probably the preferred arrangement as the strong integral part 12 will take up the side strains which are usually in direction away from the wall or pole to which the insulator support is secured. It is evident, however, that the position of the integral part could be changed and that it could, for example, be at the sides of the bracket member. Other modifications might also be possible which would still come within the scope of the invention, and I do not therefore desire to be limited to precisely what has been shown.

I claim as follows:

45 1. An insulator support comprising a bracket member formed up entire from a single piece of sheet metal, the end of said bracket member being threaded to form one side of a thimble structure, the remainder 50 of said thimble structure being formed up integral from a piece of sheet metal and secured to the bracket member.

55 2. An insulator support comprising a bracket member and a thimble structure, said thimble structure being of circular cross-section throughout, part of said thimble structure being integral with the bracket member and the other part being a separate piece and secured to the bracket member.

60 3. In an insulator support, a bracket member formed up entire from a single piece of comparatively heavy sheet metal, the end of said bracket member being of arcuate cross-section and threaded to form 65 part of the thimble structure, said bracket

member below said threaded end being of circular cross-section, and a thimble part formed entire from a single piece of thinner sheet metal secured to said bracket member at its circular cross-section and forming 70 with the threaded bracket end a thimble structure of circular cross-section throughout.

4. In an insulator support, a bracket member formed up entire from a single piece of 75 comparatively heavy sheet metal, the end of said bracket member being of arcuate cross-section and threaded to form part of the thimble structure, said bracket member below said threaded end being of circular 80 cross-section, and a thimble part formed entire from a single piece of thinner sheet metal secured to said bracket member at its circular cross-section and forming with the threaded bracket end a thimble structure of 85 circular cross-section throughout, the longitudinal edges of said thimble structure parts being separated a distance to permit radial yield of the structure when an insulator is applied. 90

5. An insulator support comprising a bracket member and a thimble structure, said bracket member being formed up entire from a single piece of comparatively heavy sheet metal and being of arch shaped 95 cross-section, the end of said bracket member being of arcuate cross-section and threaded to form part of the thimble structure, the section of the bracket member below said threaded end being of circular 100 cross-section to form a cylindrical seat, and a thimble structure part formed up entire from comparatively thin sheet metal and secured to said seat to form with said bracket member threaded end the complete thimble 105 structure of circular cross-section throughout.

6. An insulator support comprising a bracket member and a thimble structure, part of said thimble structure being integral with the bracket member and the remainder being a separate piece secured to the bracket member, said thimble parts being sub-divided longitudinally in order to yield when an insulator is applied. 110

7. An insulator support comprising a U-shaped bracket member formed up entire from a single piece of comparatively heavy sheet metal and being of arch shaped cross-section, means at the inner end of the bracket 115 for securing it to a support, the end section of the bracket member being cut out and brought together to form a base part of circular cross-section and an end of semi-circular cross-section, receiving threads on said 120 end, said end forming one-half of an insulator seat, a member of thin sheet metal and of semi-circular cross-section secured at its lower end to the base part in front of the bracket member threaded end and having 125 130

threads thereon for coöperating with the threads of the bracket member end to form the complete threaded seat for insulators, the edges of said outer seating member being separated from those of the other member for permitting relative movement between the parts when an insulator is ap-

plied, said bracket member seating end resisting the pull strains on the insulator.

In witness whereof I hereunto subscribe to my name this 1st day of February, A. D. 1916.

CHARLES L. PEIRCE, JR.
